CLAIM

The ornamental design for a breathing apparatus display screen with graphical user interface, as shown and described.

DESCRIPTION

FIG. 1 is a front view of a breathing apparatus display screen with graphical user interface;

FIG. 2 is a front view of a second embodiment thereof; and, FIG. 3 is a front view of a third embodiment thereof.

The outermost broken lines illustrate a display screen and form no part of the claimed design. The remaining broken lines illustrate portions of the graphical user interface that form no part of the claimed design.

1 Claim, 3 Drawing Sheets
